UNITED STATES PATENT OFFICE.

EMMETT W. STULL, OF WILKINSBURG, PENNSYLVANIA, ASSIGNOR, BY MESNE ASSIGNMENTS, TO ALLIS-CHALMERS MANUFACTURING COMPANY, A CORPORATION OF DELAWARE.

CIRCUIT-BREAKER.

1,116,348.

Specification of Letters Patent.

Patented Nov. 3, 1914.

Original application filed May 29, 1911, Serial No. 630,150. Divided and this application filed November 16, 1912. Serial No. 731,887.

To all whom it may concern:

Be it known that I, EMMETT W. STULL, a citizen of the United States, residing at Wilkinsburg, in the county of Allegheny and State of Pennsylvania, have invented a certain new and useful Improvement in Circuit-Breakers, of which the following is a specification.

This invention relates to electrical control systems, especially to such systems as are intended for operation from separate sources of different potential.

For reasons of economy, it has been found desirable to use higher voltages for the operation of interurban electric railways than are permissible for the ordinary city railways. The common voltage used in cities is about 600. By using double that voltage, or 1200 volts, for interurban service, a great saving in copper or in the number of substations may be effected. Since most interurban cars are also used more or less for city service, it becomes necessary in most cases to arrange the electrical apparatus on the cars which are used on such higher voltage interurban systems so that they may be used on the lower voltage city systems.

In co-pending application filed May 29, 1911, Serial No. 630,150, of which this application is a division, a control system is described as applied to the operation of the motors and auxiliary apparatus on a car of an electric railway system, whereby the car can be efficiently operated on sections of the line supplied at different potentials.

The above mentioned co-pending application describes means whereby the voltage impressed on the motor terminals and the terminals of the auxiliary apparatus is always that of the low voltage section of the line, and further describes special means for preventing the use of a set of connections unsuitable for the supplied circuit.

The objects of the present invention are, generally, to provide means for safeguarding the electrical apparatus used on the car, and, specifically, to provide a simple and efficient type of no-voltage circuit breaker for said apparatus.

The various novel features of the invention will appear from the description and drawings and will be particularly pointed out in the claims.

In the drawings: Figure 1 is a view in

elevation of a novel form of circuit breaker, 55 along with a casing, the cover of which is removed, in which the circuit breaker and related parts may be housed. Fig. 2 is a diagrammatic view showing a system for insuring the proper connections of the apparatus when the car is on the high voltage or low voltage section of the line.

The trolley wire or third rail has high and low voltage sections 22 and 23 respectively. The current from either section may be supplied to the car through a trolley or collector 24. Each car may be operated separately or there may be a number of cars controlled in common and operated together in a train. On each car are a plurality of motors M, M', arranged in one or more groups of two, but one group being shown. The two motors forming a group are connected in series for high voltage operation and in parallel for low voltage. These connections are obtained by a combined series parallel and reversing switch 25, a portion of which is shown diagrammatically in Fig. 2. This switch also reverses the relative direction of current through the field windings and armatures of such motors to obtain the desired direction of movement of the car and is specifically described in co-pending application referred to above.

In the controlling circuits is a circuit-breaker 82, biased to open position. When moved to closed position it is held there by a magnet 83, which becomes deenergized upon failure of voltage for any reason and allows the circuit-breaker to open. When open, the circuit-breaker is held in open position by a latch 84, which is not released until the magnet 83 is again energized; when the circuit-breaker may be closed by hand. The magnet 83 is in series with the operating solenoid of the main circuit-breaker 85, an overload switch 86, and the switch 87 and its operating solenoid. In shunt to the switch 87 is the solenoid 88 of the double-throw switch 89. The solenoid 88 of the switch 87 is so wound that when the trolley 24 is on a low voltage section of the line the switch 87 remains in its lower or closed position, thus short-circuiting the solenoid 88, and when the trolley 24 passes to a high voltage section the switch 87 is opened by its operating solenoid, thus throwing current through the solenoid 88 to

raise the switch 89 from its lower to its upper position.

Between the high and low voltage sections of the line there is an insulated section 90, disconnected from both the high and low voltage sections. When the car is passing from either the high or the low voltage section to the other, it passes over this section 90, thus causing the deenergization of the coil of magnet 83 and the operating coil of the circuit-breaker 85. This causes the circuit-breakers 82 and 85 to open, thus disconnecting all circuits save that including the coil of magnet 83. The passing of the trolley over the section 90 thus disconnects any motors that may have been connected for operating the car. The insulated section 90 is paralleled by a short section 91, which is preferably connected to the low voltage section 23. The section 91 is for the purpose of allowing the energization of the various circuits on the car in case the car should stop with the trolley on the section 90.

25 A switch 43, a portion of which is shown diagrammatically in Fig. 2, is provided for connecting terminals 92 or 104 to terminals 93 and 201, of circuits 94 and 202, respectively, one of which is adapted for use when 30 the car is on a high voltage section and the other when the car is on a low voltage section of the line. These circuits supply the motor control devices and the other auxiliary apparatus on the car, as specifically described in co-pending applications Serial No. 630,150, filed May 29, 1911, and Serial No. 731,886, filed Nov. 16, 1912. The double throw switch is adapted in its upper position to connect terminal 92 to the line and 40 in its lower position to connect terminal 104 to the line.

45 Assume that a car has been operating on the low voltage section 23. In order for it to operate, the switch 89 is down and the switches 43 and 25 are in low voltage position, the former to connect contacts 104 and 201 and the latter to connect the motors M, M', in parallel. When the trolley leaves the section 23 and engages the section 90, the 50 various circuits are deenergized in the manner already described. When the trolley reaches the high voltage section 22, the circuit including the magnet 83 is energized, thus releasing the latch 84, closing the circuit-breaker 85, lifting the switch 87, and throwing current through the solenoid 88 to cause it to raise the switch 89. The lifting of the latch 84 permits the manual closing of the circuit-breaker 82. The closing of the 55 circuit-breaker and the lifting of the switch 89 supplies the potential of the section 22 to the contact 92 on the switch 43. The motorman now turns the switch 43 by means of the handle 44 to move the switch 60 from low voltage position to high voltage

position, connecting contacts 92 and 93, thus energizing the circuit 94 which supplies the motor-controlling devices and the auxiliary apparatus. The car can now be started on the high voltage section of the line by the 70 operation of the motor-control system as described in my co-pending applications referred to above. In case of an overload at any time, the overload coil 100 lifts its core and closes the switch 86. This short-circuits the operating solenoid of the circuit-breaker 85, causing the opening of such circuit-breaker. This interrupts all motor circuits. Any arcing occurs at the circuit-breaker 85; this arcing may be suppressed 80 in any suitable manner. When the car passes to a low voltage section 23, the switches 87, 89, drop to their lower positions, thus connecting the contact 104 to the trolley.

85 The circuit breaker 82, shown in enlarged form in Fig. 1, comprises fixed and movable contacts 11 and 12, respectively, and electro-magnetic means for controlling the operation of the movable contact. The electro-magnet 83 comprises a core member consisting of two arms bent at angle to each other. An energizing coil 14 is mounted on one of these arms and to the extremity of the other arm is pivoted an arm 16 of magnetic 90 material to one end of which movable contact 12 is secured. The other end of the arm 16 is provided with a handle 17 for manually operating the circuit-breaker. The end of the core adjacent the coil 14 is provided with a pole face 18 against which a portion of the arm 16 is adapted to be held when the coil 14 is energized. This end of the core is also provided with an off-set extension 19 with which the end of a pivoted 100 latch 84, of magnetic material, is adapted to engage.

One convenient manner of supporting the circuit-breaker parts is shown in Fig. 1, in which the core and the fixed contact 11 are 110 rigidly secured to an insulating base 20. The latch 84 is also shown as being pivoted to this base. The core 83, the fixed contact 11, and the latch 84 are so positioned relatively to each other that the movable contact 115 12 properly engages fixed contact 11 when the pivoted arm 16 is held against the pole face 18, and that the pivoted latch 84 engages a pin on the arm 16 when the movable contact 12 is in full open position to firmly 120 secure the parts in open circuit relation, and further, that the end of the movable latch 84 may be attracted by and engage the core extension 19. The insulating support 20 with the attached circuit-breaker may be 125 positioned within a casing 21 to properly protect the circuit-breaker parts.

As shown in Fig. 1, the circuit-breaker is in open position with the circuit through the coil 14 open, a condition which will 130

exist while the trolley 24 is passing from the section of low voltage 23 to the section of high voltage 22, or vice versa. When the trolley 24 is again in engagement with a live portion of the trolley wire, the coil 14 is energized and the end of the latch 84 is drawn up to the extension 19 to release the arm 16 bearing the movable contact 12. With the parts in this position the contact 12 can be manually moved into engagement with the contact 11 and the arm 16 into engagement with the pole face 18, in which position the parts are held by magnetic attraction. The parts remain in this position until the trolley moves onto an insulating section 90 of the line, at which time the magnet 14, being deenergized, allows the arm 16 to drop and move the contact 12 to its normally open position, as shown in Figs. 1 and 2, and further allows the latch 84 to drop into engagement with the pin on the arm 16. A stop 15 may be provided to limit the opening movement of the switch to a position in which the latch 84 will properly engage the pin or projection on the arm 16.

It will be seen that in the form of invention described, gravity alone is depended upon to move the arm 16 so as to open the circuit-breaker. It will be obvious that a spring may be properly positioned to either perform this function alone or to assist the action of gravity for this purpose.

With the circuit-breaker in open position, no automatic action or jarring caused by the motion of the car can move the contacts 11 and 12 into engagement. The device disclosed insures that the motorman shall manually operate this switch before he can operate the motors or any of the auxiliary apparatus on the car.

It should be understood that it is not desired to be limited to the exact details of construction shown and described, for obvious modifications will occur to a person skilled in the art.

It is claimed and desired to secure by Letters Patent,—

1. A circuit-breaker, comprising a contact bearing arm biased to one position, a latch for holding said arm in said position, and electro-magnetic means for releasing said latch and for holding said arm in a second position independently of said latch.

2. A circuit-breaker, comprising a contact bearing arm having a portion of magnetic material and biased to one position, a latch for holding said arm in said position, and

an electro-magnet for releasing said latch and for holding said arm in a second position. 60

3. A circuit-breaking device comprising a movable contact member, means for holding said contact member in one position, and means for releasing said holding means and 65 for retaining said contact member in a second position independently of said holding means.

4. A circuit-breaker, comprising an electro-magnet having fixed and movable parts, 70 a contact attached to the movable part, and a latch for holding said movable part away from said fixed part, said fixed part adapted to release said latch and to hold the movable part in engagement with said fixed part 75 when the electromagnet is energized.

5. In a circuit-breaker, an electro-magnet having fixed and movable parts, and a latch having a portion of magnetic material for holding the movable part in one position, 80 flux through said electro-magnet releasing said latch and holding the movable part in the second position.

6. A circuit-breaker, comprising fixed and movable contacts, an arm of magnetic material attached to said movable contact, an electro-magnet comprising a core and a winding therefor, said arm being in engagement with one pole of said core and movable into engagement with the other 90 pole, and a latch of magnetic material for holding said arm out of engagement with said core and adapted to be moved out of latching position by said electro-magnet to permit movement of said arm toward said 95 second pole.

7. A circuit-breaker, comprising fixed and movable contacts, electro-magnetic means for holding said contacts in engagement and including a core and a coil thereon, an arm 100 of magnetic material pivoted to said core, and a latch for holding said arm away from one pole of said core, said pole provided with an offset pole piece adapted to attract said latch, whereby said latch is released 105 and said arm is held in engagement with said core to hold the switch contacts in engagement when the coil is energized.

In testimony whereof, the signature of the inventor is affixed hereto in the presence 110 of two witnesses.

EMMETT W. STULL.
